[57] CLAIM

The ornamental design for an electrical outlet plug, as shown and described.

DESCRIPTION

FIG. 1 is a perspective view of an electrical outlet plug showing our new design;

FIG. 2 is a top plan view thereof;

FIG. 3 is a left side elevational view, the right side elevational view being a mirror image;

FIG. 4 is a front elevational view thereof;

FIG. 5 is a rear elevational view thereof; and,

FIG. 6 is a bottom plan view thereof.

The broken lines are shown for illustrative purposes only and form no part of the claimed design.
